CLAIM

We claim the ornamental design of the combined speaker grill and saddlebag for a motorcycle, as shown and described.

DESCRIPTION

FIG. 1 is a back-side perspective of a first embodiment of a combined speaker grill and saddlebag for mounting on the clutch side of a motorcycle showing our new design;

FIG. 2 is a back-side elevation thereof;

FIG. 3 is a front-side elevation thereof;

FIG. 4 is a left end elevation thereof;

FIG. 5 is a right end elevation thereof;

FIG. 6 is a top plan view thereof;

FIG. 7 is a bottom plan view thereof;

FIG. 8 is a front-side perspective thereof;

FIG. 9 is a back-side perspective view of a second embodiment of a combined speaker grill and saddlebag for mounting on the brake side of a motorcycle showing our new design;

FIG. 10 is a back-side elevation thereof;

FIG. 11 is a front-side elevation thereof;

FIG. 12 is a right end elevation thereof;

FIG. 13 is a left end elevation thereof;

FIG. 14 is a top plan view thereof;

FIG. 15 is a bottom plan view thereof; and,

FIG. 16 is a front-side perspective thereof.

The broken lines in the figures illustrate environmental elements of the design in position of use and form no part of the claimed invention.
